OVERLAPPING CURTAIN DEVICE

Jacob Tendrich and Max Tendrich,
New York, N. Y.

Application March 22, 1940, Serial No. 325,318

3 Claims. (Cl. 156—10)

This invention relates to a device to be attached to a draw curtain in a manner to provide overlapping curtain edges. We refer to curtains which ordinarily have meeting or abutting edges such as are used in bath rooms for showers, or in Pullman cars, beauty shops, hospitals, tents, dressing rooms and other places where draw curtains are used to temporarily screen a space. In such places it is desirable for reasons of privacy, or in bath rooms to prevent splashing of water, that the edges of the curtains be overlapping. In such curtains as ordinarily constructed or already installed the overlapping of the edges is not possible.

The object of the invention is to provide a device which may be built into the curtain when it is manufactured or which may be attached to an already installed curtain whereby when the curtain is drawn, overlapping edges may be provided for. In the drawing illustrating the invention—

Fig. 1 is a fragmentary view illustrating the usual manner in which such curtains are hung and operated.

Fig. 2 is a similar view illustrating curtains provided with an overlapping device according to this invention.

Fig. 3 is a fragmentary view of a curtain supported by a curtain overlapping device according to this invention which device is built into the curtain as a part of its manufacture.

Fig. 4 illustrates the same device as in Fig. 3 but used as an attachment to an already constructed curtain.

Fig. 5 is a detail view of an eyelet device.

Fig. 1 shows a curtain rod 10 which supports two curtains 11 and 12 having meeting edges 13 and 14 when the curtains are drawn together as shown. The two parts 11 and 12 may of course represent the two end portions of a single curtain, a shower curtain for instance. The usual safety pin type curtain hooks 15 slide upon the rod 10 and pass through eyelets 16 in the curtain to support it. As is well known, when such curtains are drawn the edge portions tend to spread. The object of the invention is to provide means for overlapping the curtain edges. Fig. 2 shows the same curtain supported in a manner according to this invention. The device itself is not shown but it will be seen that the hooks 15 at the edges 13 and 14 are omitted and that when the curtains are drawn the next two outermost hooks 17 and 18 meet and whereby the end portions overlap as indicated by the positions of the

edges 13 and 14 thus accomplishing the object of the invention.

The device is simplicity itself. As shown in Fig. 3 it consists of a single straight flat bar or member 20 secured to the curtain by eyelets 21 through which the hooks 15 are passed as usual. The edge eyelet may be closed as indicated at 22 so that when the curtain is hung it will be impossible to place a hook near the edge thereof. 10 When the curtain is hung the overlapping portion will be in place without requiring any particular care or special effort as to spacing of the hooks or the like. Preferably the eyelets 21 which secure the curtain to the bar 20 are spaced some what closer than the other eyelets whereby the fabric may hang in folds below the bar. The portion 24 of the bar supports the overlapping portion of the curtain. The other portion 25 balances the portion 24 and prevents it from tipping 20 by turning around a single eyelet as will be understood. It will be noted from Fig. 3 that the overlapping bar is completely concealed within the top seam of the curtain and does not mar the appearance of the curtain. This is an obvious advantage.

The bar may be entirely separate from the curtain as shown in Fig. 4 in which a bar 26 is a flat piece of any suitable material provided with three holes 27 spaced somewhat closer than the eyelets in the curtain. The hooks will be passed through two of the holes 27 and through the corresponding eyelets 16 in the curtain. The hooks, not shown, will then be in the same positions as the hooks in Fig. 3. A fastener 28 will be supplied with instruction to put it through the outermost hole in the bar.

The holes in the bars in Figs. 3 and 4 may be fitted with soft rubber eyelets 40 as shown in Fig. 5 to prevent the bars from riding up upon the hooks and become tangled.

The overlapping curtain device in Fig. 3 consists of a bar which may be built into the curtain when it is manufactured and secured with eyelets for the hooks. At the corner there need not be any eyelet but a fastener 22 will suffice to secure the fabric at that point. In Fig. 4 the bar is separate and hung upon either side of the curtain in the usual hooks. It then serves the same purpose. The separate fastener 28 is provided to avoid confusion in hanging the bar and serves also to secure the fabric. The device may be used at one or both ends of a curtain.

We claim:

1. In a shower curtain device for providing overlapping curtain edges the combination with

a shower curtain having a folded seam along its top edge forming a pocket along said edge, of an overlapping curtain bar member inserted within said pocket to be entirely concealed within the same and means securing said overlapping curtain bar member to the curtain.

2. In a shower curtain device for providing overlapping curtain edges the combination with a shower curtain having a folded seam along its top edge forming a pocket along said edge, of a flat overlapping curtain bar member inserted within said pocket to be entirely concealed therein, spaced eyelets passing through said curtain and bar member for suspending the same by curtain hooks and for positioning said bar member within said pocket seam to extend from the edge of the curtain a distance within said pocket to include at least three of said spaced eyelets.

3. In a shower curtain device for providing overlapping curtain edges the combination with a shower curtain having a folded seam along its top edge with spaced eyelets therethrough for suspending said curtain from curtain hooks passing through said eyelets, of an overlapping curtain bar member having openings spaced to match with the said eyelets in the curtain for the passage of curtain hooks through said eyelets and said openings and other means passing through one eyelet opening adjacent the edge of the curtain and through one of said bar openings near one end of the bar for securing the said bar member to the curtain.
